UNITED STATES PATENT OFFICE.

GEORGE Q. SEAMAN, OF NEW YORK, N. Y.

TRUSS.

No. 872,851.

Specification of Letters Patent.

Patented Dec. 3, 1907.

Application filed February 28, 1907. Serial No. 359,713.

To all whom it may concern:

Be it known that I, GEORGE Q. SEAMAN, a citizen of the United States, and a resident of the city of New York, borough of Brooklyn, in the county of Kings and State of New York, have invented a new and Improved Truss, of which the following is a full, clear, and exact description.

This invention relates to trusses such as 10 worn by persons suffering from a rupture or hernia. The object of the invention is to produce a device of this class which can be readily applied to the body and which may be securely retained in its proper position, the arrangement being such that the pressure of the pad at the point of rupture may be controlled or adjusted.

The invention consists in the construction and combination of parts to be more fully 20 described hereinafter and particularly set forth in the claims.

Reference is to be had to the accompanying drawings forming a part of this specification, in which similar characters of reference 25 indicate corresponding parts in both figures.

Figure 1 is a perspective of a truss constructed according to my invention, and indicating the manner in which it is applied 30 to the body; and Fig. 2 is a cross section through the device, taken in the vicinity of the pad.

Referring more particularly to the parts, 1 represents the main frame of the device, 35 which is preferably formed of stout bar bent into substantially the form of a horse-shoe. The illustration represents a truss for the left side, and in this instance, the main frame 1 is applied to the body from the left 40 side. The ends of the frame 1 are formed into elongated downwardly projecting eyes 2, which are connected by an adjustable strap 3 at the right side of the body, it being understood that the view is taken from the 45 rear. By means of an adjusting buckle 4, the strap 3 may be tightened so as to fasten the frame 1 securely to the body.

To the main frame 1, on the forward side and in the vicinity of the ruptured point, an 50 adjusting frame 5 is pivotally attached by means of sleeves 6, said sleeves passing around the adjacent portion of the frame 1, as shown. The frame 5 is formed with curved extensions 7 and 8, the former of 55 which passes around the left side of the body, while the latter of which passes around the

right side of the body. As illustrated, these extensions do not completely surround the body, but simply extend around the hips of the person wearing the truss. The rear ends 60 of the extensions 7 and 9 are bent downwardly and formed into eyes 9 similar to the eyes 2 aforesaid, and these eyes 9 are connected by an adjusting strap 10 having an adjusting buckle 11, as indicated. Between the sleeves 6 the adjusting frame 5, which is also formed of wire similar to the frame 1, is bent downwardly to form a loop or pad-frame 12. Upon this loop 12 a pad 13 is formed, the same being of slightly crescent form, as indicated in Fig. 1. As shown in Fig. 2, the arrangement is such that when the parts are in their normal position, the loop 12 projects inwardly toward the body. In this way the loop has the effect of a short 75 arm projecting inwardly and carrying a pad. Evidently, the relation of the pad 13 will depend upon the level of the extensions 7 and 8; that is, if the extensions 7 and 8 are held more elevated than usual, the 80 pad 13 will project farther toward the body, and vice versa.

In order to enable the position of the pad to be regulated, I provide a pad adjusting strap 14. This strap depends from the rear 85 portion of the main frame 1 and supports the adjusting strap 10. It is provided with an adjusting buckle 15. It should be understood that the strap 10 is not drawn tight enough to bind the adjusting frame 5 tightly 90 against the body. This frame is free at all times to be raised or lowered. It tends, of course, to hang downwardly so that the pad constantly exerts pressure upon the body. The outer pressure upon the pad, of course, 95 maintains the strap 14 taut, the strap operating to limit the outward movement of the pad.

In the manner described, a very light and efficient truss is produced, which is readily 100 applied to the body, which can be worn without discomfort, and which can be readily adjusted so as to suit the requirements of the patient.

Having thus described my invention, I 105 claim as new and desire to secure by Letters Patent:

1. A truss having a main frame adapted to be secured to the body, an adjusting frame comprising a bar rotatably mounted on the 110 side of said main frame and having an inwardly projecting arm, a pad carried on said

arm and adapted to press over the position of the rupture, said adjusting frame having extensions removed from said main frame, and means for adjusting said adjusting frame 5 toward said main frame to support the pressure on said pad.

2. A truss comprising a main frame adapted to be applied to the body and having a bar projecting across the front of the 10 body, an adjusting frame pivoted to said bar at the front and having an arm formed thereupon projecting inwardly toward the body, a pad formed on said arm, said adjusting frame having extensions at the side of said 15 main frame, and means for adjusting the pivotal position of said adjusting frame upon said main frame to support the pressure on said pad.

3. A truss comprising a main frame 20 adapted to substantially surround the body, an adjusting frame pivotally attached on said main frame at the front and extending toward the rear of the body, an arm carrying a pad formed on said adjusting frame and 25 projecting toward the body, and means for

drawing said adjusting frame toward said main frame at the rear thereof to support the pressure on said pad.

4. A truss having a main frame of substantially horseshoe form adapted to be applied to the body from the side, adjustable means for connecting the ends of said main frame at the side of the body, an adjusting frame pivotally attached to said main frame at the forward side thereof and having an 30 arm formed thereupon, a pad carried on said arm and projecting toward the body, said adjusting frame having curved extensions passing around the sides of the body, an adjusting strap connecting said curved extensions, and an adjusting strap supporting said adjusting frame from said main frame at the rear.

In testimony whereof I have signed my name to this specification in the presence of 45 two subscribing witnesses.

GEORGE Q. SEAMAN.
